UNITED STATES PATENT OFFICE.

JESSE B. HAWLEY, OF WILMETTE, ILLINOIS.

SOUND-AMPLIFYING HORN.

Original application filed February 23, 1923, Serial No. 620,579. Divided and this application filed February 24, 1925. Serial No. 11,145.

My invention relates to an improved sound amplifying horn which is constructed in such a manner that the usual undesirable tonal qualities inherent in other horns are 5 eliminated.

One of the objects of my invention is to provide an improved sound amplifying horn constructed with relatively soft horn walls so as to substantially eliminate resonance. 10 A further object of this invention is to provide a novel sound amplifying horn composed of accretions of interlaced fibers.

Yet another object resides in providing a sound amplifying horn composed of accretions of interlaced fibers wherein the superficial fibers of the relatively soft horn wall are compressed and, or, otherwise to provide a wall having zones of variant density which tend to deaden resonance. 15

20 A further object is to provide a sound amplifying horn having an interlaced fiber wall wherein the superficial fibers of the relatively soft horn wall are suitably treated to provide a somewhat smooth or polished surface thereby to provide surfaces of greater sound reflecting efficiency and of greater durability.

Another object of this invention resides in providing a simple and inexpensively manufactured sound amplifying horn. 30

These and other objects of the invention will be apparent from a perusal of the following specification when taken in connection with the accompanying drawings, 35 wherein:—

Figure 1 shows in section and elevation the apparatus for producing a horn of the character referred to.

Figure 2 shows in fragmentary sectional elevation the construction of a part of the apparatus shown in Figure 1. 40

Figure 2^a is a fragmentary elevation showing a certain feature of the present construction, while Figure 2^b is a fragmentary section designed to show other features thereof. 45

Figure 3 is a longitudinal sectional elevation showing one stage in the process of manufacturing a horn in accordance with my present invention.

50 Figure 4 is a longitudinal sectional elevation showing another stage in the process of manufacture.

Figure 5 is a similar view showing another stage in the manufacture of the improved horn.

55 Figure 6 is a longitudinal section of a

horn constructed in accordance with the present invention and having applied to the exterior face thereof a coating.

And, Figure 7 is a cross section showing 60 both outer and inner faces of the horn as provided with coating material.

The present application is a division of my pending application Serial No. 620,579, filed February 23, 1923, wherein my improved horn and the method of making it 65 is disclosed and claimed.

Referring more in detail to the annexed drawings, numeral 1 designates the former, or mandrel on which is formed the sound 70 horn. During the first two stages of the process of manufacture of a horn this former is secured to the upper end of a pipe 2 which may be connected by means of a flexible connector to a suction device for 75 the purpose of withdrawing liquid through the former to cause formation of a deposit on the exterior face thereof. Where the pipe 2 passes through the bottom of a container 3 there is a packing gland 80 4 to prevent leakage of the fluid from the container around the pipe 2. To the upper end of the pipe 2 is secured a plate 5, preferably by means of screw threading. The plate 5 is shown as having its upper face 85 hollowed out to form a concavity 6 into which liquids may drain to be carried off by means of pipe 2.

The former comprises a core 7 together with a plurality of layers of material arranged 90 thereover. The core 7 is provided with a plurality of longitudinal and transverse grooves connected at their lower ends, by means of openings 8, with the concavity 6. Fitting closely over the surface of the core 7 is a 95 perforated sheet metal form 9 which serves to support on the core 7 a fine mesh wire netting 10 and prevent the same from being distorted by pressure upon the surface thereof. Around the lower beveled edge of the core 100 7 is arranged a flexible band 11, preferably constructed of rubber, the purpose of which will appear hereinafter. In the construction shown in Figure 1 there is provided a vibrating apparatus 12 for the purpose of 105 vibrating the upper portion of the container 3 to keep the contents thereof in agitated condition and to assist in causing uniform deposit of the fibrous materials upon the form. While applicant has disclosed a 110 single means for vibrating a portion only of the container, this is to be understood as

2
illustrative only since applicant has devised other means for agitating the liquids, including mechanism for simultaneously vibrating both the top and bottom of the container.

5 It is also found very satisfactory to cause agitation of the suspension by means of a jet or jets of air forced into the receptacle in which the suspension is contained.

The apparatus shown in Figure 4 is for 10 the purpose of carrying out a stage in the method of making the horn subsequent to those stages which are carried out in the apparatus of Figures 1 to 3 inclusive. This apparatus comprises a base plate 13 corresponding to the base plate 5 of the previously described apparatus, said base plate having a concave upper surface from which leads a pipe 14 for drawing off liquids from the interior of the apparatus. A plunger 15 or like device 15 forces the plate 13 up against the bottom of the container 16 which is prevented from moving upwardly by means of a rigid portion of the apparatus against which the top of container 16 presses. 20 Opening through the wall of container 16 is a pipe 17 by means of which steam can be admitted to cause drying thereof.

Figure 5 shows a mechanism for further compacting the felted or interlaced fibers 30 and then burnishing the outer surface thereof. This mechanism comprises, in the form shown, a bar 18 on which slides a frame 19 carrying a bevel gear 20 adapted to be rotated by any suitable means. The bevel 35 pinion is carried by a shaft which may be driven from any suitable source of power which does not need to be shown herein. A shaft 22 is preferably mounted at an angle to the bar 18 and carries thereon a burnishing 40 member 23 comprising a plurality of separately rotatable parts which rotate at different speeds as the horn is rotated by the driving of the bevel pinion 21.

In the carrying out of my new method the 45 pipe 2 is pushed upwardly through the packing gland 4 until it occupies the dotted line position shown in Figure 1 and a liquid containing therein suspended fibrous felt or cotton linters, rag stock or other soft, suitable 50 fibers is poured into the container 3 until it is well above the position which the top of the former will occupy when lowered into the tank 3. The former 1, comprising parts 7, 9, 10 and 11 is placed on the base 5 and 55 lowered into the container, to the position shown in Figure 1. Suction apparatus connected to the pipe 2 is now operated to cause the withdrawal of the liquid through the former 1. This causes a deposit of the fibers 60 upon the fine mesh wire netting 10 and this operation is continued until fibers of the desired thickness have been deposited upon the former. On a commercial scale the container is large enough so that any desired number 65 of horns may be made at one time. When a

sufficient amount of the fibers have been deposited upon the former to suit the requirements of the operator, the suction is reduced and the suspended material and liquid removed from the container. Another suspension, such as paper pulp in water, is now introduced into the container 3 to substantially the same height as before and the suction is increased to cause withdrawal of the liquid through the former and deposit of a 70 layer of pulp upon the outer surface of the felt or other fibers previously deposited. As will be obvious, there is considerable pressure upon the surface of the netting as the felt is being built up thereon, but the netting is sustained by the metal form 9 upon which it rests, and this in turn is sustained by the core 7. The liquid reaching perforations 8 by way of the longitudinal and transverse channels cut in the surface of the core passes 75 into the chamber 6, as will be readily understood, and is withdrawn therefrom through the pipe 2 by the suction apparatus. By reason of the operation of the vibrating apparatus 12 or other agitation, as by air jets, 80 the liquid and the particles suspended thereby are kept in constant agitation and suspension and the particles are prevented from settling to the bottom of the container. 85 This also, together with the suction, causes the fibers to be deposited in accretions, the fibers interlacing and tending to arrange themselves substantially parallel to the direction of the surface as formed. The vibrating apparatus shown is merely typical of 90 any one of several which I may employ and which may be used to vibrate the upper portion of the container as shown, or may be used to vibrate both the top and bottom thereof. Also, vibration is to be understood 95 as typical of any mode of keeping the suspension in agitation. It should perhaps be stated that during the operation just described the member 11 rests on the edge of the core 7 to prevent deposit of the fibrous materials thereon.

When the operation above described has been completed the former is preferably raised to the dotted line position shown in Figure 1 and the band 11 is turned up over the edge of the felt as shown in Figure 4. The former and deposited felt are then placed on the table or platform 13 and enclosed within the container 16 which, as heretofore indicated, is held tightly against the edge of the core by upward pressure upon the supporting member 15. Live steam is then introduced through the pipe into the container 16 and passes through the formed horn and the former and out through pipe 14. This results in sufficient pressure upon the fibers to compact the same and the steam has a tendency to evaporate the moisture from the felt and cause a reasonable drying 120 thereof. The purpose in turning the band 125 130

11 over the edge of the formed horn is to prevent the same from running out in a thin edge over the former and to give proper shape to said edge.

5 When the horn has been properly compacted and dried in the manner shown in Figure 4, the former and horn are removed to the spindle 24 connected with bevel gear 20, which spindle is non-circular in form 10 and fits into a correspondingly shaped opening in the bottom of the core 7. After the parts have been arranged as shown in dotted lines in Figure 5, the bracket 19 is moved longitudinally along bar 18 until bevel gear 15 meshes with pinion 21. Rotation of the bevel pinion 21 will now cause the horn to be turned in contact with the burnisher which is made up of separate parts, so that the different sections of the horn and bur- 20 nisher may turn at substantially the same peripheral speed notwithstanding their different and varying radial dimensions. Be- sides burnishing the surface of the horn this loosens the horn from the form. After the 25 horn has been finished in the manner indicated the horn and former are separated and the surface of the horn may be coated either internally or externally or both, in any de- sired manner, as, for example, by metallizing, 30 by painting, by varnishing, or shellacking. One method of metallizing is by spraying molten metal upon the surface thereof. In the constructions shown in Figures 6 and 7, numeral 25 is used to designate the inner 35 or felt layer, 26 the outer or pulp layer, 27 the outer coating and 28 the inner coating. Whether one or both surfaces of the horn will be coated will depend upon the character of use which is to be made of this horn 40 and the character of tones which it is desired to have produced thereby. These considerations will also determine the characteristics of the coating material to be used.

By "felting material", as used in this specification and claims, is meant a material made from fibers which are interlaced or intertwined in a promiscuous manner but substantially parallel to the direction of the surface being formed.

50 Some people prefer to have the external surface of the horn left rough, as it is before submission to the burnisher or calendering machine, and, when this type of finish is desired, the burnishing or calendering step is omitted.

Also, when the type of construction required necessitates a reversal of the steps of the process, this reversal may be accomplished by using a hollow form lined with netting or having an equivalent construction. This former is then placed within a container and the two are connected in an air-tight manner so that when suction is applied to the container the liquid of the pulp, felt, or other suspension, will be drawn through

the form to deposit the fibrous material on the interior thereof. By this method it will be possible to secure a rough inner surface if desired, as pointed out above with regard to the outer surface.

70 While in most cases it is desirable to have an inner dense layer backed by a softer layer, even this is not universal, since, in some cases, it is preferable to have a soft layer for the inner surface. The arrangement of layers must be chosen in accordance with the characteristics of the sound which it is desired to produce. In this connection it is noted that the horn may be made up of several layers of varying degrees of 75 compactness or hardness. This is accomplished by using suspensions of different grades of fibrous material and applying each of them for a short period of time. The fineness of the fibrous material may be regulated by the length of time the material is beaten when being prepared.

80 From the foregoing description it must be evident that the process disclosed is peculiarly adapted to the production of sound 85 amplifier horns, first because any shape of horn may be easily made by merely changing the shape or configuration of the porous former; second, because of the manner in which the horn wall is built up by accretions 90 of fibers which lay themselves, relatively loosely, under the influence of the suction, on the porous former and therefore the horn wall is characteristically relatively soft and tends to dampen resonance which is usually 95 set up in rigid elastic walls by the sound vibrations; third, because of the compacting of the superficial fibers of the horn wall, as by suitable pressure (in the illustrated instance by steam pressure, or by the pressure 100 incident to the burnishing operation) which compacting provides a relatively harder or more dense exterior wall and a softer interior or core. This wall of combined hard 105 and soft portions is even more peculiarly 110 adapted to dampen resonance. Fourth, because the smoothing of the exterior surfaces of the wall as by burnishing and coating with paint, varnish or shellack or the like, 115 provides a somewhat polished sound reflecting surface which materially augments the amplification of the sound.

120 It is therefore understood that the specific description of structure and methods set forth above may be departed from without departing from the spirit of my invention.

Having now described my invention, I claim:

1. A sound horn comprising a layer of 125 felt and a layer of pulp.
2. A sound horn comprising a layer of felt and a layer of pulp and a finish for the surface thereof.
3. A sound horn comprising a layer of 130 felt, a layer of pulp exterior thereto and

1. having its exterior face burnished, and a finishing material upon the inner face thereof.
2. A sound horn comprising a layer of fibrous animal matter, a layer of fibrous vegetable matter exterior thereto and having its exposed face burnished and covered with a finishing coat, and a coat of finishing upon the inner face thereof.
3. A sound horn comprising a layer of fibrous animal matter, a layer of fibrous vegetable matter exterior thereto, the exposed face of the layer of fibrous animal matter being burnished, and the exposed faces of the horn having a coat of finishing material applied thereto.
4. As a new article of manufacture, a sound horn, comprising a layer of felted animal fibers and a layer of felted vegetable fibers.
5. As a new article of manufacture, a sound horn comprising a layer of felted animal fibers and a layer of felted vegetable fibers, and a layer of coating material applied to the surface of the horn.
6. A sound horn comprising a layer of hard felted fibrous material and a layer of soft felted fibrous material.
7. A sound horn comprising a layer of hard felted fibrous material and a layer of soft felted fibrous material, the inner surface of the horn body being hard.
8. A sound horn comprising inner and outer fibrous layer portions, the inner portion being harder than the outer portion.
9. A sound horn comprising layers of felted fibrous material graduated in hardness from one surface to the other.
10. A sound horn comprising walls composed of a layer of felt fiber and a layer of pulp fiber, a portion of the fibers of these adjacent layers being intermingled.
11. A sound horn comprising walls composed of a layer of felt and a layer of pulp exterior to the layer of pulp, the exterior face of the horn being burnished and the interior face of the horn having a finishing material thereon.
12. A sound amplifying horn comprising walls composed of a layer of felt and a layer of pulp exterior to the layer of pulp, the exterior face of the horn being burnished and the interior face of the horn having a finishing material thereon.
13. A sound amplifying horn comprising walls composed of a layer of felt and a layer of pulp exterior to the layer of pulp, the exterior face of the horn being burnished and the interior face of the horn having a finishing material thereon.
14. A sound amplifier having walls comprising accretions of interlaced fibers, certain of which are more closely compacted than others whereby to provide a less resonant sound wall.
15. A sound amplifier having walls comprising accretions of interlaced fibers including a strata of felt fibers and a strata of pulp fibers.
16. A sound amplifier having walls comprising accretions of relatively loosely interlaced fibers, the superficial fibers of the wall being compacted.
17. A sound amplifier having walls comprising accretions of relatively loosely interlaced fibers, whereby to dampen resonance in said walls.
18. A sound amplifier having walls comprising accretions of relatively loosely interlaced fibers, the superficial fibers being compacted and smoothed to provide sound reflecting surfaces.
19. A sound horn having walls comprising accretions of interlaced fibers of pulp the superficial fibers of the horn wall being compacted, smoothed and coated to provide sound reflecting surfaces and substantially non-resonant walls.
20. A sound horn comprising a layer of hard felted fibrous material and a layer of soft felted fibrous material, the fibers of the adjacent surface of the two layers being interlaced.
21. As a new article of manufacture, a sound horn, comprising a layer of felted animal fibers and a layer of felted vegetable fibers, a portion of the fibers of one layer being intermingled with a portion of the fibers of the other layer.
22. A sound amplifier having walls comprising two layers of accretions of interlaced fibers, the fibers in one layer being of a different material than the fibers in the other layer and a portion of the fibers in one layer being interlaced with a portion of the fibers in the adjacent layers.
23. As a new article of manufacture, a sound horn having a wall comprising accretions of interlaced fibers, the fibers in a portion of the walls being of a different material and having different resonance characteristics than the fibers in another portion of the wall.
24. A sound horn having a wall comprising accretions of interlaced fibers, the fibers in one portion of the walls being of a different material and having different resonance characteristics than the fibers in an adjacent portion of the wall, fibers in one portion being interlaced with fibers in the adjacent portion.
25. A sound horn comprising accretions of interlaced fibers.

In witness whereof, I hereunto subscribe my name to this specification.
